CLAIM

The ornamental design for a honeycomb paper dispenser, as shown and described.

DESCRIPTION

FIG. 1 is a first perspective view of a honeycomb paper dispenser showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the using state of the honeycomb paper dispenser thereof; and,

FIG. 10 is a perspective view of the using state of the honeycomb paper dispenser thereof.

The broken lines shown in the drawings depict portions of the honeycomb paper dispenser that form no part of the claimed design.
